UNITED STATES PATENT OFFICE.

ARTHUR W. BURKS, OF DECATUR, ILLINOIS.

PUMP.

Application filed February 14, 1921, Serial No. 444,830. Renewed January 15, 1927.

This invention relates to pumps, and more particularly, to pumps of the centrifugal type, comprising a rotor having fluid impelling means, such as a series of blades, operating within a raceway, there being a relatively tight fit between the rotor and the casing to resist the flow of fluid from the raceway.

An object of the invention is to provide a pump having a novel rotor construction, and one in which the relative arrangement of the rotor impelling means and raceway are different from devices heretofore known in the art, resulting in a more satisfactory and efficient principle of operation.

Another object of the invention is to provide means for reducing, to a minimum, eddy currents, and other power decreasing conditions which generally exist adjacent the inlet opening of this type of pump, and also to minimize the loss of power at the outlet after the fluid has left the rotor.

The above-mentioned and other objects of a more minute character, which will become obvious as the description proceeds, are attained by a construction which comprises a casing having a raceway open at one side only, and into which, through the open side, projects a series of blades adapted to act upon the fluid entering through a suitable inlet opening and making its exit through an outlet opening also provided. The rotor is, preferably, arranged in a plane parallel to the plane of the raceway, the blades projecting laterally from the margin of the rotor through the open side of the raceway into the latter.

The impelling blades are arranged in an annular marginal series upon the disk-shaped rotor, and each blade is provided with a concave impelling face. Each blade should, preferably, though not necessarily, project from the face of the rotor for the same distance throughout its width.

In order to minimize the loss of power adjacent the inlet and outlet openings of the raceway each opening communicates with a passageway, the cross-sectional area of each passageway gradually increasing in a direction away from its opening.

The above are the more important and general features with which the invention

is characterized, and in the accompanying drawings I have shown a pump in which they are embodied. In these drawings:

Fig. 1 is a front elevational view of the pump, a portion of the same being shown in cross-section,

Fig. 2 is a side view with the upper half of the casing and rotor shown in cross-section,

Fig. 3 is an enlarged detail view of a portion of a rotor,

Fig. 4 is a view similar to Fig. 3 showing a slightly modified blade construction, and

Fig. 5 is a fragmentary sectional view taken longitudinally of the inlet opening.

Referring to the drawings more in detail, 10 indicates a casing section formed with a marginal raceway or chamber 11 having an inlet opening 12 and an outlet opening 13. 70 The raceway is open only at one side, 13, this side being open entirely around the raceway. A rotor 14 is also located within the casing in a plane paralleling the plane of the raceway, and is formed with a marginal flange 15 from which laterally project, away from one face of the rotor, a plurality of spaced blades 16. The blades and flange extend through the open side 13 of the raceway into the latter, and it will be noted that 80 the raceway has an open space surrounding the blades 16. This open space extends from the inlet opening in a clockwise direction (Fig. 1) to the outlet opening 13. Between the outlet opening and the inlet opening the 85 raceway narrows and is of only a sufficient width to permit the blades and flange to pass between the side walls 11'. By thus narrowing the raceway, leakage of the fluid, which has been carried around the raceway 90 to the outlet opening, back to the inlet opening is prevented. The rotor is fixedly mounted upon a shaft 17 which has bearings in the central portion of the casing section 10, and in a boss 19 of a rear casing section 95 20. The forward end of the shaft may be surrounded by a bushing 18', and the rear end of the boss 19 may be closed by a gland nut 21 serving to retain within the boss packing 22. The two casing sections may be held 100 together by any suitable means, such as screws 23 passing through peripheral flanges

on the sections, and the rotor shaft may be operated from any prime mover through pulley 24 positioned thereon. One of these pulleys will, of course, be a loose pulley 5 which is employed whenever it is desired to maintain the pump inoperative.

Referring to the rotor construction (Fig. 4) it will be noted that each blade 16 is formed with a concave impelling face 16' and projects from the face of the rotor or flange 15 for the same distance through its entire width. The blades may have the flat end faces 16'' shown in Fig. 4, or, if preferred, these faces may be curved, as shown in the 10 modified construction of Fig. 3. The blades are arranged in the annular marginal series in order to travel through the raceway, as shown in Figs. 1 and 2, and initially engage the fluid as it enters the raceway through 15 the inlet opening 12 which directs the fluid at an angle to the face of the rotor and communicates with a passageway 25 formed in a suitable nozzle 26, into which the end of 20 a supply pipe may be inserted. This passageway gradually increases in cross-sectional area in a direction away from the inlet opening so that the fluid will have its 25 velocity gradually increased to the velocity of the fluid within the raceway, thereby 30 preventing the creation of eddy currents, decreasing the impact between the entering fluid and the rotor and effectively guarding against other power consuming conditions.

By referring to Fig. 1 it will also be noted 35 that the outlet opening 13 communicates with a passageway 27 in a nozzle 28, this passageway also gradually increasing in cross-sectional area as it leads away from the outlet opening 13. By this arrangement 40 the loss of power due to friction at the outlet is prevented, for it will be understood that the fluid leaving the rotor has a very high velocity head which would be quickly lost through the friction if it is not 45 quickly changed to pressure head. By employing the diverging passageway or nozzle shown the high velocity head of the fluid is quickly changed to pressure head with very little loss of total head.

50 Another important feature of the invention resides in the relation of the cross-sectional areas of the inlet and outlet openings to the cross-sectional area of the unoccupied portion of the raceway. As will be evident 55 from an inspection of the drawings, the raceway has an open space surrounding the rotor blades, and the cross-sectional area of this open space is the same as the cross-sectional area of the inlet and outlet openings, the outlet opening being indicated at 60 13. That is to say, the area of each opening is at least equal to the cross sectional area of the raceway on a radial plane minus the cross sectional area of the space occupied 65 by the ring of blades, whereby the inlet

opening is adapted to supply a sufficient amount of fluid to maintain the raceway at substantially its operating capacity.

In operating this pump, power is applied to the rotor shaft 17 and the rotor is revolved in a clockwise direction, as viewed 70 in Fig. 1. Fluid entering through the inlet opening 12 is engaged by the blades, generally upon the inner side of the blades, and the centrifugal force immediately results in 75 a tendency to throw the water against the outer wall of the raceway, the centrifugal force being modified by a forward or tangential force created by the revolution of the rotor. The path actually taken by the so fluid is a resultant of these two forces. Each amount of fluid operated upon in this manner, of course, obtains a great increase in velocity. This increase in velocity head of the fluid is immediately imparted in the 80 form of pressure head to the fluid immediately ahead in the raceway, and the impartation of power results in an immediate decrease in head on the part of the amount of fluid which again is actuated by the rotor. 85 In passing through the raceway the fluid follows the helical course indicated by the dotted lines in Figs. 3 and 4 until it reaches the outlet opening, where its very high 90 velocity head is changed to pressure head by the diverging nozzle 28 above described. The frequency with which the fluid is actuated by the rotor during its passage through the raceway will vary in accordance with 95 the back pressure at the outlet, high back pressure at the outlet tending to lengthen the path of the fluid by increasing the number of times it is subjected to the action of the rotor. This will be more clearly understood by comparison of the dotted lines shown in Figs. 3 and 4. In Fig. 4 it will 100 be noted that the curves are less sharp and more gradual than the curves in Fig. 3. In Fig. 4 the dotted lines correspond to the course of the fluid under low back pressure, 105 the fluid moving a further distance after it is once thrown outwardly by the impeller than in Fig. 3. In Fig. 3 it will be noted that the curves are sharp due to the fact 110 that the high back pressure prevents fluid from passing onwardly within the raceway for any considerable distance before it imparts its velocity head to the fluid which has preceded and returns to the rotor for impulsion.

115 In addition to the action of the rotor, the form of the raceway changes the direction of the water and causes it to take the helical path, and if no other force acted to change 120 its course or reduce its velocity, it would again enter the impeller at a point farther ahead in the direction of its rotation, when it would again receive kinetic energy from the action of the impeller. Due to the small 125 friction of the discharge and the friction of 130

the passage through the raceway, in addition to the head, the pump may be acting against, the water leaving the impeller will encounter a back pressure or pressure head acting in a direction opposite rotation of the impeller. This force tends to change the course of the water counter to the direction in which it is traveling. The water in thus changing its direction gives up its velocity head to the 10 water just ahead of it in the form of the pressure head. As the water gives up its velocity head to the water in advance, it is caused, by the several forces mentioned, to return to the impeller to obtain additional 15 velocity, and the path it takes is a helical one.

The water does not in any substantial or considerable amount pass through the narrow portion of the raceway. Small amounts 20 of the same may return to the inlet opening, but not in degrees sufficient to affect the operation of the pump.

Although I have described, in detail, a concrete embodiment of my invention, it should 25 be understood that the showing and description is merely illustrative, and not in any sense restrictive of the invention, such modifications being possible without departing from the invention as come within the scope 30 of the following claims.

I claim:—

1. A pump comprising a rotor having an annular marginal series of blades positioned 35 on a lateral face thereof, said blades having unshrouded ends whereby the spaces between the blades are open at the ends of the blades, and a casing having a fluid raceway enclosing said series of blades, there being a space within the raceway between the ends of the 40 blades and the wall of the raceway.

2. A pump comprising a rotor having an annular marginal series of blades positioned 45 on a lateral face thereof, said blades having unshrouded ends whereby the spaces between the blades are open at the ends of the blades, and a casing having a fluid raceway in a plane parallel to the plane of the rotor enclosing said series of blades, there being a space within the raceway between the ends of the blades and the wall of the 50 raceway.

3. A pump comprising a rotor having an annular marginal series of blades positioned 55 on a lateral face thereof, said blades having unshrouded ends whereby the spaces between the blades are open at the ends of the blades, and a casing having a fluid raceway in a plane parallel to the plane of the rotor enclosing said series of blades, said raceway being closed to the remainder of the rotor, there being a space within the raceway between the ends of the blades and the wall of the raceway.

4. A pump comprising a rotor having an 60 annular marginal series of blades positioned

on a lateral face thereof, said blades having unshrouded ends whereby the spaces between the blades are open at the ends of the blades, a casing having a fluid raceway in a plane parallel to the plane of the rotor 70 enclosing said series of blades, and means for admitting fluid to said raceway at an angle to the face of the rotor, there being a space within the raceway between the ends of the blades and the wall of the raceway. 75

5. A pump comprising a casing having a circular chamber therein open at one side only, said chamber having an inlet and an outlet opening, and a rotor located in a plane parallel to the plane of said chamber 80 and having a marginal series of blades extending laterally from a face thereof into said chamber side opening and closing the latter, there being a space in said chamber surrounding said blades. 85

6. A pump comprising a casing having a narrow annular chamber therein open at one side only, said chamber having an inlet and an outlet, a rotor located in a plane parallel to the plane of said chamber, and a marginal circular series of comparatively small 90 blades extending laterally from a face of said rotor through the side opening into the chamber and closing said opening, said blades being narrower than the chamber. 95

7. A pump comprising a casing having a narrow annular chamber therein open at one side only, said chamber having an inlet and an outlet, a rotor located in a plane parallel to the plane of said chamber, and a marginal circular series of comparatively small blades extending laterally from a face of said rotor through the side opening into the chamber and closing said opening, said blades being narrower than the chamber and 100 each blade having a transversely curved impelling surface. 105

8. A pump comprising a casing having a narrow annular chamber therein open at one side only, said chamber having an inlet and an outlet, a rotor located in a plane parallel to the plane of said chamber, and a marginal circular series of comparatively small blades extending laterally from a face of said rotor through the side opening into the chamber and closing said opening, said blades being narrower than the chamber and each blade having a transversely curved concave impelling surface. 110

9. A pump comprising a disk rotor, a circular marginal series of blades positioned 115 on a lateral face thereof, said blades having unshrouded ends whereby the spaces between the blades are open at the ends of the blades, a circular fluid raceway for said blades, said raceway having an inlet opening and an outlet opening, the ends of said blades being spaced substantially from the wall of the raceway. 125

10. A pump comprising a disk rotor, a cir- 130

cular marginal series of blades positioned on a lateral face thereof, said blades having unshrouded ends whereby the spaces between the blades are open at the ends of the blades,
 5 a circular fluid raceway for said blades, said raceway having an inlet opening and an outlet opening, the ends of said blades being spaced substantially from the wall of the raceway, and said inlet opening being
 10 adapted to admit fluid at an angle to the face of the rotor.

11. A pump comprising a casing having a chamber therein open at one side only, said chamber having an inlet and an outlet opening, and a rotor located in a plane parallel to the plane of said chamber and having a marginal series of blades extending laterally from a face thereof into said chamber side opening and closing the latter, said
 15 inlet and outlet openings each being of an area at least equal to the cross-sectional area of the unoccupied portion of said chamber.

12. A pump comprising a casing having a chamber therein open at one side only, said chamber having an inlet and outlet opening, and a rotor located in a plane parallel to the plane of said chamber and having a marginal series of blades extending laterally from a face thereof into said chamber side opening and closing the latter, said inlet and outlet openings each being of an area at least equal to the cross-sectional area of the unoccupied portion of said chamber, and each having a passageway communicating therewith which gradually increases in cross-sectional area in a direction away from its opening.

13. A pump comprising a substantially disc-like rotor, a substantially circular series of blades positioned on a lateral face of said rotor remote from its axis, said blades having unshrouded ends whereby the spaces between the blades are open at their ends, a casing for said rotor having a substantially circular fluid raceway into which said blades project, said raceway having an inlet opening and an outlet opening and the casing making a substantially fluid-tight fit with the rotor on opposite sides of the blades, the sealing surfaces of the casing and rotor being at a substantial angle to a plane normal to the rotor axis.

14. A pump comprising a substantially disc-like rotor, a substantially circular series of blades positioned on a lateral face of said rotor remote from its axis, said blades having unshrouded ends whereby the spaces between the blades are open at their ends, a casing for said rotor having a substantially circular fluid raceway into which said blades project, said raceway having an inlet opening and an outlet opening and the casing making a substantially fluid-tight fit with the rotor on opposite sides of the blades, the sealing surfaces of the casing and rotor

being disposed at an angle to the lateral face of the rotor, and the walls of said raceway being spaced from the blades whereby there is a substantial cross-sectional area of the raceway unoccupied by the blades.

15. A pump comprising a substantially disc-like rotor, a substantially circular series of blades positioned on a lateral face of said rotor remote from its axis, said blades having unshrouded ends whereby the spaces between the blades are open at their ends, a casing for said rotor having a substantially circular fluid raceway into which said blades project, said raceway having an inlet opening and an outlet opening and the casing making a substantially fluid-tight fit with the rotor on opposite sides of the blades, the sealing surfaces of the casing and rotor being substantially parallel with the rotor axis, and the walls of the raceway being spaced from the blades at their ends and sides whereby there is a substantial cross-sectional area of the raceway at the ends and sides of the blades unoccupied by the latter.

16. A pump comprising a rotor having an annular marginal series of blades and a casing having an annular channel therein forming a raceway for fluid to be impelled by said blades, said casing forming a substantially water-tight joint with the surface of said rotor on each side of said series of blades to form a substantially closed fluid raceway, the sealing surfaces between the casing and rotor on opposite sides of said series of blades being disposed at angle to the lateral surface of the rotor.

17. A pump comprising a rotor having an annular marginal series of blades and a casing having an annular channel therein into which the blades project forming a raceway for fluid to be impelled by said blades, said casing forming a substantially water-tight joint with the surface of said rotor on each side of said series of blades to form a substantially closed fluid raceway, the sealing surfaces between the casing and rotor on opposite sides of said series of blades substantially paralleling the rotor axis.

18. A pump comprising a rotor having an annular series of blades remote from its axis and projecting outwardly from the plane of a lateral face of the rotor and a laterally projecting flange on the rotor at the inner ends of said blades providing pump casing sealing surfaces disposed on opposite sides of the blades and substantially at a right angle to the lateral face of the rotor.

19. A pump comprising a rotor having an annular series of blades remote from its axis and projecting outwardly from the plane of a lateral face of the rotor and a laterally projecting flange on the rotor at the inner ends of said blades providing substantially imperforate pump casing sealing surfaces

disposed on opposite sides of the blades and substantially paralleling the rotor axis.

20. A pump rotor comprising a substantially disc-like element having a centrally disposed axis of rotation and an annular marginal series of blades projecting outwardly and laterally from the plane of a lateral face of the rotor, and shoulders disposed at the inner ends of said blades on

said rotor having casing sealing surfaces arranged on radially opposite sides of the series of blades, said surfaces being disposed at a substantial angle to the lateral face of the rotor.

In testimony whereof I have hereunto set my hand.

ARTHUR W. BURKS.
